UNITED STATES PATENT OFFICE.

KARL P. NEILSEN, OF LONG BEACH, CALIFORNIA.

OIL PUMP.

Application filed October 8, 1925. Serial No. 61,338.

My invention is particularly applicable to oil well pumps, and consists in certain novel improvements in the pump plunger, plunger valve, and their association with the 5 sucker rod of the pump.

In present pumps having their plunger valve located above the plunger and their sucker rod connected to the upper end of the valve cage, it has been found that 10 sand, scale etc. are deposited around the valve cage and nut due to the fact that their external diameters are necessarily less than that of the pump plunger, and under the action of the weight of the column of oil 15 above the plunger and during reciprocation of the latter, the sand, scale etc. are forced downwardly between the co-acting surfaces of the plunger and liners, thereby scoring the surfaces, and resulting in the sticking of 20 the plunger.

An object of my invention is to provide means whereby the sand, scale etc., is prevented from accumulating between the plunger and the liners.

25 Another object is to provide a pump assembly which is simple, and in which a number of threaded joints, heretofore considered essential are eliminated.

A further object is to provide a simple 30 and effective connection between the pump plunger and the sucker rod.

Other objects advantages and features of 35 invention may appear from the accompanying drawing, the subjoined detailed description, and the appended claims.

In the drawing illustrating my invention Fig. 1 is a longitudinal sectional view of one form of my pump.

Fig. 2 is a longitudinal sectional view of 40 another form of my pump with the standing valve not shown.

Fig. 3 is a sectional view on line 3—3 Fig. 2, with the jacket and liners omitted.

Fig. 4 is a sectional view on line 4—4 45 Fig. 3.

Referring more particularly to the drawing, my pump includes a tubular plunger 1, which is reciprocally mounted in a jacket 2 in which liners 3 are placed to provide a 50 wearing surface for the plunger.

The plunger 1 is a running fit in the liners 3 and the upper end thereof is chamfered as at 4, to form a sharp upper edge which skims the sand etc. from the walls of the 55 liners, throwing the sand inwardly and

causing it to be carried out of the well with the stream of oil.

To further prevent sticking of the plunger 1, I may provide lubricating means for the walls of the liners 3 and plunger, which 60 consists of a plurality of annular grooves 5 in the plunger, in which oil is trapped and is fed to the wearing surfaces of said plunger and liners, during reciprocation of the 65 plunger.

For the larger plunger diameters about 2 inch i. d. more or less, I may extend the sucker rod there-through, and provide a connection at the bottom of the plunger, 70 although I may also connect the sucker 75 rod to the top of the plunger as will be described. A sleeve 6 is provided with threads 7 on which the lower threaded end of the plunger 1 is secured. An extension 8 on the sleeve 6 is formed with an internally threaded box 9 into which the usual pin of the sucker rod 10 is screwed. Elongated ports 11 in the extension 8 permits passage of 80 oil from the sleeve 6 to the inside of the plunger 1.

A second sleeve 12 screws into the lower end of the sleeve 6 and a valve seat 13 is clamped between said sleeves. A check ball 14 rests on the seat 13 and a pin 15 retains 85 said ball in position.

A standing valve 16 of any well known construction is positioned in the bottom collar 17.

For smaller pump sizes in which the passage through the plunger would be very materially obstructed, I prefer to connect the sucker rod to the upper end of said plunger. If desired the following construction may 90 also be applied to large pump sizes.

A sucker rod connector 18 is threaded at 95 the lower end 19 thereof, and screws into the upper end of the plunger 1. A lock nut 20 screws into the upper end of the plunger 1, and the connector 18 is seated thereagainst, thus preventing said connector from unscrewing. A central opening 21 is provided through the nut 20, to permit passage of oil 100 therethrough.

The connector 18 is counter bored as at 22 from the lower end thereof, and elongated 105 ports 23, extend thru the wall of the connector into said counter bore to permit the passage of oil therethrough into the jacket 2 and flow pipe, from the plunger 1. A box 24 is provided at the upper end of the con- 110

- necter 18 and the threaded pin 25 of the sucker rod 26 screws therein. An enlarged guide 27 is formed on the connector 18 between the box 24 and the top of the ports 23, the faces of which bear against the liner 3, to guide and prevent wobbling of the sucker rod 26. Flat faces 28 are provided on the guide 27, which serve as a wrench hold, and permit the passage of oil.
- 10 A sleeve 29 is threaded into the lower end of the plunger 1 and a valve seat 30 is clamped between said sleeve and plunger. A ball check 31 is seated on the valve seat 30. The usual standing valve 16 is positioned below the sleeve 29 as shown Fig. 1.
- 15 My pump construction is of particular advantage when used in connection with a cup stand, in which the cups are below the plunger, in that all sand, grit etc. are kept away from the cups thereby materially lengthening their usefulness.
- 20 The construction hereinbefore described is obviously applicable to different types of pumps than those that are shown, and I do not wish to limit myself to the particular form shown.
- 25 The operation of my pump is identical to the well known reciprocating plunger pump.
- 30 Having described my invention I claim.
1. In an oil pump a tubular plunger, a sucker rod connector screwed into said plunger, sucker rod connecting means on said connector, lock means in said plunger for said connector, and valve means depending from said plunger.
  2. In an oil pump a tubular plunger, a sucker rod connector screwed into said plunger, sucker rod connecting means on said connector, lock means in said plunger for said connector, and valve means depending from said plunger.

40 sucker rod connector screwed into said plunger, sucker rod connecting means on said connector, lock means in said plunger for said connector, and valve means depending from said plunger, and a scraping edge on the upper end of said plunger.

45 3. In an oil pump, a tubular plunger, a sucker rod connector screwed into the upper end of said plunger, said connector having a passage therethru for the free passage of oil, lock means in said plunger for said connector, a box on said connector adapted to receive the sucker rod, and valve means depending from said plunger.

50 4. In an oil pump a tubular plunger, a sucker rod connector screwed into the upper end of said plunger, a lock nut screwed into said plunger against said connector, said connector having a passage therethru for the free passage of oil, a box on said connector adapted to receive the sucker rod, a guide on said connector, and valve means depending from said plunger.

55 5. In an oil pump a tubular plunger, a sucker rod connector screwed into the upper end of said plunger, a lock nut screwed into said plunger against said connector, said connector having a passage therethru for the free passage of oil, a box on said connector adapted to receive the sucker rod, a guide on said connector, and valve means depending from said plunger.

60 In testimony whereof I affix my signature.

KARL P. NEILSEN.
